CAP STRUCTURE FOR BOTTLES

James Ellis Underwood, Phoenixville, Pa., assignor to The West Company, Phoenixville, Pa., a corporation of Pennsylvania

Application May 28, 1951, Serial No. 228,721

3 Claims. (Cl. 215—38)

1

This invention relates to cap structure for pharmaceutical bottles and the like whose contents are to be sealed against contamination and are to be accessible by insertion of a needle through the cap structure. Such cap structures essentially comprise a resilient sealing member usually formed of rubber, and a cap usually formed of metal which is secured to the bottle and which has a tear-off portion to expose an area of the sealing member and thus enable insertion of a needle through said member.

Heretofore cap structures of the general type and character above-mentioned have involved a number of objections and disadvantages. The separate parts have necessarily been handled separately and have been brought together in an assembled structure only at the time of application to bottles. This has involved considerable waste due to damage to the individual parts which are more fragile individually than when assembled, and it has also made storage and maintenance difficult due to the fact that it has been necessary to store or maintain a stock of component parts. It has also involved considerable time and labor cost due to the necessity of handling the separate parts.

A further disadvantage is present in prior cap structures employing a sealing member in the form of a disc. Application of such a cap structure to a bottle has frequently caused a downward cupping of the sealing disc due to the fact that the disc is placed under compression. Since rubber does not compress under a compressive force but tends to expand under such force, there is a tendency for the disc to cup downward into the neck of the bottle, and this provides a small recess or catch basin for dirt or dust, making it difficult for the physician or surgeon to avoid contamination of the needle used to extract the contents of the bottle.

One object of the present invention is to eliminate the above-mentioned objections of prior cap structures.

Another object of the invention is to provide a simple cap structure which may be manufactured and automatically assembled prior to usage and which effects economies by virtue of its being capable of assembly as a unit which may be handled, shipped and stored, and which may be easily applied as a single unit to a bottle or other container at any time. Thus a pharmaceutical manufacturer can autoclave, rumble or otherwise sterilize and handle the assembled cap structure without fear that the component parts will become disassembled.

Other objects and features of the invention will be apparent from the following detailed description with reference to the accompanying drawing wherein

Figs. 1 to 4 are perspective views of the component elements or parts of one embodiment of the invention, the parts shown in Figs. 1 and 4 being broken away and sectioned for the purpose of illustration.

2

Fig. 5 is a sectional view of the cap assembly taken diametrically therethrough, showing the parts after they have been brought together but prior to the crimping securement;

5 Fig. 6 is a similar view showing the completed cap structure after crimping securement of the parts;

Fig. 7 is a sectional view showing the cap structure applied to a bottle, said view also being taken diametrically through the cap structure;

10 Figs. 8 to 10 are sectional views generally similar to Figs. 5 to 7, showing a modified form of the cap structure;

Fig. 11 is a fragmentary perspective view of the inner retaining member; and

Fig. 12 is an enlarged fragmentary perspective view of the assembled and applied cap structure.

Referring first to Figs. 1 to 7 of the drawing, the cap structure provided by the present invention essentially comprises a relatively deep circular outer cap 10 formed of aluminum or other suitable material, a circular resilient sealing member 11 preferably in the form of a disc and formed of rubber or other suitable material, and having a depth substantially less than the depth of cap 10, and a retaining member 12 generally in the form of a ring and having an inturned flange 13 at the top thereof, and also preferably having an outturned flange 14 at the bottom thereof to enable crimping securement as hereinafter described. If desired, the cap structure may also include a facing element 15 in the form of a disc composed of nylon or other suitable material, said element serving as a facing for the sealing member 11.

15 After manufacture of the above-mentioned component parts, the parts are brought together as shown in Fig. 5. The sealing member 11 seats within the upper part of the cap 10, and assuming that the facing element 15 is employed, this element is placed within the cap 10 against the sealing member 11. The retaining member 12 is nested within the lower part of cap 10. With the lower part of the retaining member 12 formed as shown, the lower edge of cap 10 rests upon the flange 14 as shown in Fig. 5.

20 After the parts have been brought together in assembled relation, as shown in Fig. 5, the flange 14 is curled or crimped about the lower edge of cap 10, as shown in Fig. 6, with the edge of flange 14 pressed inwardly against the outer surface of cap 10. The firm frictional engagement between the curled or crimped flange 14 and the lower part of cap 10 serves to hold the parts securely in assembled relation.

25 As clearly shown in the drawing, the cap 10 is provided with a tear-off portion 16, and this portion may take the form disclosed and claimed in U. S. Patent No. 2,425,269 issued March 22, 1949, to LeRoy H. Rohde et al. and assigned to the assignee of the present application.

30 As clearly shown in Figs. 5 and 6, the circular sealing member 11 preferably has a diameter less than the internal diameter of the cap 10 but

greater than the inner diameter of the turned flange 13 on the retaining member 12. Whether or not the facing element is employed, the flange 13 serves to retain the sealing member 11 within the upper part of cap 10.

After completion of the assembled cap structure as shown in Fig. 6, the same may be handled, shipped, stored and subjected to any desired sterilizing treatment, without fear of the parts becoming disassembled. As previously pointed out, this is a very important advantage over prior cap structures of this general type or character.

Whenever it is desired to apply the cap structure to a bottle, as shown in Fig. 7, the assembled cap structure is placed over the head 17 of the usual bottle 18, and the lower portions of parts 10 and 12 are crimped inwardly by rolling beneath the head 17 and against the bottle neck. Of course it will be understood that the parts are dimensioned to enable such attachment to the bottle. In applying the cap structure to the bottle, downward pressure is exerted to effect a tight seal, and due to this pressure the resilient sealing member 15 flows or expands outwardly, and this is permitted without causing any distortion of said member by reason of the space made available for outward expansion of member 11 due to the fact that its diameter is less than the internal diameter of the cap 10. Therefore there is no tendency for the sealing member 11 to cup downward as previously mentioned.

When it is desired to use the contents of the sealed bottle 18 it is merely necessary to remove the tear-off portion 16 of the cap 10 and then insert a needle through the exposed portion of sealing member 11 and through the facing element 15, assuming that the latter is used. Since there is no cupping of the sealing member 11, there is no recess or catch basin wherein dirt or dust might accumulate.

In Figs. 8 to 12, there is shown a modified form of the cap structure which differs from the first-described form in certain respects. In this instance, as shown in Fig. 8, the relative depths of the outer cap 10a and the inner retaining member 12a are such that the lower portion of cap 10a is adapted to be curled or crimped inwardly about the lower edge portion of the member 12a, as shown in Fig. 9. It will be seen that this is a reversal of the crimping arrangement employed in the first-described embodiment.

The embodiment shown in Figs. 8 to 12 also includes a feature which may be employed in any embodiment of the invention. The turned flange 13a of the retaining member 12a has an upwardly turned edge 19 which is directed toward the sealing member 11a and the facing disc 15a, assuming that the latter is employed. With this feature incorporated in the cap structure, it is preferable to employ a bottle or container 18a having an inclined sealing surface as shown at

20.

Figs. 10 and 12 show the cap structure after application to a bottle 18a under pressure as previously described. It will be noted that the upwardly turned edge 19 performs a biting action, and where the facing disc 15a is employed as shown, the edge bites into this element and stretches it across the mouth of the bottle. This is due to the fact that during the pressure application of the cap structure to the bottle, the retaining member 12a is deformed where it engages the top of the bottle, and the edge 19 is caused to exert outward radial forces on the disc 15a.

While certain embodiments of the invention

have been illustrated and described, it is to be understood that the invention is not limited thereto, as it will be obvious that various modifications are possible. For example, the sealing member 11 may take forms other than that shown, such as a stopper, and may be formed of materials other than rubber, such as cork. The other parts of the structure may also be varied as to form and composition.

I claim:

1. A cap structure for pharmaceutical bottles, comprising a relatively deep outer cap, a resilient sealing member seated within said cap, and a retaining member nested within said cap and having an turned flange at its top to retain said sealing member, said flange having a turned biting edge directed toward said sealing member, said cap and said retaining member being secured together by crimping securement of their lower edges, said retaining member and said cap being adapted to fit over the top of a bottle and to be crimped inwardly to secure the entire cap structure permanently to the bottle.

2. A cap structure for pharmaceutical bottles, comprising a relatively deep circular outer cap, a circular resilient sealing member seated within the upper part of said cap, said sealing member having a depth substantially less than the depth of said cap, and a retaining member nested within the lower part of said cap and having an turned flange at its top to retain said sealing member, said flange having a turned biting edge directed toward said sealing member, said cap and said retaining member being secured together by crimping securement of their lower edges, said retaining member and the lower part of said cap being adapted to fit over the top of a bottle and to be crimped inwardly to secure the entire cap structure permanently to the bottle.

3. A cap structure for pharmaceutical bottles, comprising a relatively deep circular outer cap, a circular resilient sealing member seated within the upper part of said cap and having a diameter less than the internal diameter of said cap, said sealing member having a depth substantially less than the depth of said cap, and a retaining member nested within the lower part of said cap and having an turned flange at its top to retain said sealing member, said flange having a turned biting edge directed toward said sealing member, said cap and said retaining member being secured together by crimping securement of their lower edges, said retaining member and the lower part of said cap being adapted to fit over the top of a bottle and to be crimped inwardly to secure the entire cap structure permanently to the bottle, said sealing member expanding radially when subjected to compressive force during application of the cap structure to a bottle.
